CHILD'S GARMENT

Verne L. Stephenson, Goshen, Ind., assignor to
 Snuggle Rug Company, Goshen, Ind., a corporation of Indiana

Application February 3, 1937, Serial No. 123,788

1 Claim. (Cl. 2-80)

The invention relates to improvements in outer garments for children and more particularly to children's garments of the union type.

Garments of the above general character, while made in numerous styles for both indoor and outdoor wear, are particularly suitable as winter garments for young children. When well made of good quality material, such garments are capable of giving satisfactory service through several 10 seasons before the material becomes worn out. As a general thing, however, a garment that fits the child properly and presents a neat, attractive appearance initially, is outgrown long before the full wear is obtained from the garment.

15 With the foregoing in view, it is the primary object of the invention to provide a child's union type garment which may be readily adjusted as the child grows so as to fit properly initially and throughout the life of the garment.

20 Another object is to provide an improved union garment which may be easily and quickly put on over the child's ordinary clothing.

Other objects and advantages of the invention will become apparent from the following detailed 25 description of the preferred embodiment illustrated in the accompanying drawing, in which

Fig. 1 is a front view of a garment embodying the features of the invention.

Fig. 2 is a top view of the garment shown in 30 Fig. 1.

Fig. 3 is a sectional view taken along the line 3-3 of Fig. 1 showing the construction at the waist band.

Fig. 4 is a sectional view similar to Fig. 3, but 35 showing the garment adjusted to maximum size.

Fig. 5 is a sectional view similar to Fig. 3, but showing a modified form of construction.

Fig. 6 is a sectional view taken along the line 40 6-6 of Fig. 3 showing the manner of attaching the belt loops.

The garment selected to illustrate the invention is of the so called "ski suit" or "snow suit" type designed for outdoor wear and includes a body portion and a legging portion joined together at the waist line. It may be made of any suitable material such as heavy wool or part wool fabric which provides the desired warmth, and it may be lined with a closely woven fabric to render it windproof. Such garments may be 45 worn by either children or adults, but are most commonly used for children below the teen age.

As garments of the above type are designed to be worn over the ordinary clothing, they must be provided with relatively large openings so that 50 they can be put on and taken off without too much difficulty. Heretofore, it has been the practice to provide an opening for this purpose in the form of a slit extending longitudinally of the body portion of the garment, usually down the front from the neck to the crotch. In the pres-

ent invention, this longitudinal slit is dispensed with and suitable transverse openings are provided in the shoulder portions and the crotch so that the garment may be readily put on or taken off by slipping it over the head or the feet of the child. Alternatively, a comparatively short slit 5 may be provided in the front of the garment, for example, a slit terminating at a point substantially above the waist line which, in conjunction with the crotch opening, permits the garment to be put on or taken off as above explained.

It will be apparent that, with the openings in the garment arranged in the above manner, the body portion and the upper part of the legging portion may be made continuous and joined together at the waist line by a seam extending entirely around the garment and unbroken by any longitudinal opening. Advantage is taken of this arrangement to provide a fold or lap of material at the seam which may be utilized subsequently to lengthen the garment when desired. Thus, by reason of the advantageous arrangement of the openings, the body and legging portions of the garment may be joined together in a novel manner to provide a garment which may 20 be readily adjusted to fit a child properly at varying stages of growth so that full wear may be obtained from the garment.

As will be seen by reference to the drawing, the garment, in its preferred form comprises a continuous body portion 10 having sleeves 11 and 12 and a legging portion 13 having legs 13^a and 14. The arms 11 and 12 may conveniently terminate in cuffs 15 of knitted or other flexible fabric for snugly embracing the wrists or adjacent parts of 25 the arm. Similar cuffs 16 on the legs 13^a and 14 provide a tight fit around the angles.

Suitable openings are provided in the body portion 10 to permit the garment to be put on by slipping it over the child's feet. In the particular form illustrated, these openings comprise slits 17 and 18 in the arms 11 and 12, respectively, the slits extending from the neck of the garment across the shoulders and down the arms approximately to the cuffs 15. Alternatively, a 40 single opening extending down the front of the garment may be provided in place of the slits 17 and 18, such opening terminating at a point substantially above the waist line. Any suitable means such as slide fasteners 19 may be 45 used to close the openings.

The garment may include a collar 20 of any suitable type. As herein shown, the collar 20 comprises a front section 21 and a rear section 22 attached respectively to the front and back 55 panels of the garment as defined by the slits 17 and 18, the two sections together extending entirely around the neck. To provide a snug fit and yet permit the collar sections to be separated when the garment is put on or taken 60

off, the sections may be detachably fastened together at the ends as by buttons 23 which, in the present instance are sewed to the rear section 22 and adapted to cooperate in suitable button holes 24 formed in the front section 21.

As it is sometimes desirable to put on the garment by slipping it over the child's head, a suitable opening may be provided in the legging portion 13 for this purpose. This opening is 10 preferably in the form of a slit 25 extending from the cuff 16 of the leg 14 up along the inner side of the leg, through the crotch, and down the inner side of the leg 13^a and its cuff 16. Any suitable means may be employed for closing 15 the slit. A slide fastener 26 of the so called "open" type has been found to be particularly suitable for this purpose as it permits the edges of both cuffs to be separated thus making it a simple matter to put on or take off the garment. When the leg opening above described 20 is used, it is desirable to retain the sleeve openings 17 and 18 to assist in getting the child's arms into the sleeves.

With the construction above described it is 25 unnecessary to provide an opening extending across the waist line of the garment such as has heretofore been the usual practice. Accordingly, the body and legging portions may be made in a continuous piece at the waist line so 30 that they may be joined together by an unbroken seam 27 extending entirely around the garment.

In the manufacture of the garments, the body portion 10 or the legging portion 13 is made substantially longer than required for the initial 35 size of the completed garment. For example, in the case of a size 6 garment, that is, a garment designed to fit the average six-year old child, one of the parts may be sufficiently long for a size 7 or even a size 8 garment. The parts are 40 assembled initially by arranging the legging portion and the body portion in overlapping relation and sewing them together by a row of stitching 28 adjacent the edge of the normal length portion but spaced a predetermined distance inwardly from the edge of the oversize portion. 45 The spacing of the seam from the edge of the oversize portion is determined by the length required for a size 6 garment, that is, the seam is made at the point where the said oversize portion would end if cut exactly to size 6 length. 50 Thus, when the parts are sewed together, a strip of material 29 extends beyond the seam 27 and is available for lengthening the garment when desired.

As will be seen by reference to Fig. 3, the 55 upper edge of the fabric forming the legging portion 13 is turned in as at 30 so as to lie along the outside of the fabric forming the body portion 10 and the stitching 28 passes through both 60 layers of fabric. Thus, the stitching is not apparent from the outside of the garment and the strip 29 is inside where it does not show.

The garment may also be provided with a belt 31 of any suitable type held in place by loops 65 32 which may be made of the same material as the main part of the garment. As herein shown, the loops are sewed to the garment, one end being interposed between the edge 30 and the flap 29 as shown in Fig. 6 so as to be held in place by the stitching 28, the other end being 70 stitched to the body portion as at 33 at a point substantially above the seam 27.

When the garment is to be lengthened, the

stitching 28 is removed by cutting or otherwise and the turned in edge 30 is resewed to the flap 29. If maximum length is desired, the new seam will be made close to the lower edge of the flap as shown in Fig. 4. For intermediate 5 lengths, the seam may be made at points suitably removed from the edge of the flap according to the length desired. The belt loops 32 are also removed and resewed to the garment in the same relative position as before so that the belt serves to cover the newly exposed portion of the fabric which previously constituted the flap 29. This is particularly important when the garment is lengthened after a substantial amount of wear as the color of the newly exposed fabric will naturally differ slightly from that of the rest of the garment. Thus, the belt 31 effectually covers the area presented by the new material so that the variation in color will not be noticeable.

In the modified form shown in Fig. 5, the upper edge 34 of the legging portion is turned in to correspond in length to the flap 29 and the parts are secured together along their edges by stitching 35. A second row of stitching 36 joins the parts at a point spaced substantially in from the edge and defines the initial seam between the body and legging portions of the garment. In this case, the belt loops 32 are attached to the garment at their lower ends by the stitching 36. 30

When the garment is to be lengthened, the stitching 36 is cut leaving the stitching 35 to join the parts together. Intermediate sizes may be obtained, of course, by resewing at points intermediate the stitching 35 and the stitching 36. 35 After each adjustment, the position of the belt loops 32 is altered as above described.

It will be apparent from the foregoing that the invention provides a novel and useful union type garment for children. By reason of the advantageous arrangement of the openings in the sleeves and legs, the body and legging portions of the garment may be joined in an advantageous manner which permits lengthening the garment when required. Thus the garment may be made to fit snugly initially and may be adjusted from time-to-time as the child grows so as to fit properly throughout the life of the garment.

I claim as my invention:

A child's outer garment including a waist section, said waist section having a neck opening and sleeves terminating in cuffs of flexible material with slits in each sleeve extending outwardly from the neck opening and along the tops of the sleeves to facilitate insertion of the child's arms in the sleeves, said waist section being continuous across the front and back and having means for closing said slits, collar members attached to the front and rear edges of the neck opening and detachably secured together at their ends in alignment with the inner ends of said slits, and a trouser section joined to said waist section by an uninterrupted seam extending around the garment at the waist line and providing an extension portion of surplus material for lengthening the garment, said trouser section having an opening for slipping the garment over the child's head comprising a slit extending through the crotch and down the inner side of each leg and means for closing said last mentioned slit.

VERNE L. STEPHENSON.
